UNITED STATES PATENT OFFICE.

FRANCIS HARTER, OF WILKES-BARRÉ, PENNSYLVANIA.

WAGON-BRAKE.

SPECIFICATION forming part of Letters Patent No. 278,948, dated June 5, 1883.

Application filed April 5, 1883. (Model.)

To all whom it may concern:

Be it known that I, FRANCIS HARTER, a citizen of the United States, residing at Wilkes-Barré, in the county of Luzerne and State of Pennsylvania, have invented certain new and useful Improvements in Wagon-Brakes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has relation to improvements in wagon-brakes; and it consists in the construction, combination, and arrangement of the several parts, as will be hereinafter described, and pointed out in the claims.

In the drawings, Figure 1 is a front view, and Fig. 2 is a vertical longitudinal section, of a section of a wagon having my brake mechanism applied thereto.

The wheels *a a'* are spindled on the ends of axle *A*, which is preferably secured or connected to the wagon-platform by springs, &c., substantially as shown. Bars *b b* are pivoted to the axle near the inner ends of the hubs of the wheels, and are carried forward to a point somewhat in advance of the wheels, and are hinged to the lower ends of bars *c c*, the upper ends of which bars are pivoted or hinged on the platform-bar *d*.

The brake-shoes *e* are secured on the opposite end of a rod, *e'*, and rest against the wheels, as shown. When so desired, these shoes may have a slight turning or rocking movement on the rod, so that they will readily adapt themselves to the periphery of the wheel. Connecting-rods *f f* are fixed to the rod *e'*, and extend forward, and are coupled or hinged to the bars *b c* at the hinge-joint of the latter, as shown, thus forming a connection between the rods *b c* and the brake-rod, and furnishing a support for the latter. It will be seen that the brake-rod *e'* extends across from wheel to wheel, and that I employ two each of the bars *b c* and connecting-rods *f*, arranged on opposite sides, as shown. In order to hold the brake-shoes against or away from the wheels

and to regulate the force of bearing thereof, I employ the lever *g*, which is pivoted in a suitable bracket or other support connected to the framing, and its lower end is connected with the brake-rod *e'*, at about the middle thereof, by the pitman *h*, so that as the lever *g* is operated the brake-shoes will be held against the wheels, as shown in full lines, or away therefrom, as indicated in dotted lines, Fig. 2. This lever may be operated by means of the rod *i*, connected to its upper end, and extended forward and provided with the handle *i'*; or other operating means may be employed—such, for instance, as a chain might be secured to the upper end of the lever *g*, and carried forward and made fast to a foot or hand lever arranged in reach and under the control of the driver.

In the ordinary brakes used on spring-wagons the brakes are usually supported from the wagon-platform, and as the load is put on the body settles and the brake-shoes are carried below what is usually termed the "bulge" of the wheel, and the greater portion of their braking action is lost. By the connections and arrangement of the mechanism before described the settling of the wagon-platform has little or no effect on the position of the brake-shoes, the latter remaining in approximately the same position when the wagon is loaded as when it is not, and arranged to bear at all times on about the same portion of the wheels. The brake-shoes, it will be seen, are held at a point above the bulge of the wheels, so that as the latter are revolved there is a kind of wedging action which aids in the braking operation, enabling the brake to be strongly applied with but little exertion on the part of the driver. The brake being also connected with or mainly supported by the axle, the springs are relieved from all strain.

It will be understood that in the drawings I have only illustrated one—the rear—half of a wagon, that being the portion to which the brakes are ordinarily attached.

Having thus described my invention, what I claim, and desire to secure by Letters Patent, is—

1. In a wagon-brake, the combination, substantially as described, with axle and the brake-

- shoes supported on rod e' , of the bars $b\ c$, having their adjacent ends hinged together, and their opposite ends hinged, respectively, to the axle and to the platform-bar, the connecting-
 5 rods $f\ f$, having one end secured to the brake-shoes and their other ends pivotally secured on the hinge-joint between the rods $b\ c$, the lever g , the pitman h , and means for operating the said lever, substantially as specified.
- 10 2. In a wagon-brake, the combination of the brake-shoe arranged to bear on the wheel at a point above a horizontal line drawn through the axis thereof, and a bar pivoted to and extended from the axle forward beyond the wheel, and providing a pivotal support for the brake-shoe at a point in advance of and below the bearing-point thereof, whereby a wedging action of the brake-shoe is obtained, and the rod
 15
- h' , having one end pivoted to the rod e' and extended rearward, with its other end secured to the operating mechanism, all arranged to operate substantially as specified.
3. In a wagon-brake, the combination of the rods $b\ c$, hinged together and supported substantially as described, the brake-shoes supported on a suitable rod, and the connecting-
 20 rods f , and means for operating the brake, all arranged and operating substantially as and for the purposes set forth.
- 25 In testimony whereof I affix my signature in presence of two witnesses.

FRANCIS HARTER.

Witnesses:

PHILIP O'NEILL,
 J. R. PERRY.
